TEXTILE FABRIC OR SIMILAR ARTICLE

Theodore H. Koeber, Oak Park, Ill., assignor to International Harvester Company, a corporation of New Jersey

Application March 4, 1952, Serial No. 18,773

Term of patent 14 years

(Cl. D92—1)

To all whom it may concern:

Be it known that I, Theodore H. Koeber, a citizen of the United States, and residing at Oak Park, in the county of Cook, Illinois, have invented a new, original, and ornamental Design for a Textile Fabric or Similar Article, of which the following is a specification, reference being had to the accompanying drawing, forming a part hereof.

The figure of the drawing is a plan view of a piece of textile fabric, showing my new design. The design unit includes four symmetrically arranged squares having four figures in each square, which unit is repeated over the textile fabric as indicated.

I claim:

The ornamental design for a textile fabric or similar article, as shown and described.

THEODORE H. KOEGER.
